UNITED STATES PATENT OFFICE.

LEONORE BUBENHEIM, OF NEW YORK, N. Y., ASSIGNOR TO MADAME LEONORE ART DOLL CO., OF NEW YORK, N. Y., A CORPORATION.

DESIGN FOR A DOLL.

Application filed February 19, 1924. Serial No. 8,675. Term of patent 7 years.

To all whom it may concern:

Be it known that I, LEONORE BUBENHEIM, a citizen of the German Republic, residing at New York, in the county of Bronx and State of New York, in the United States of America, have invented a new, original, and ornamental Design for Dolls, of which the following is a specification, reference being had to the accompanying drawing, forming part thereof.

The figure is a front elevation of a stuffed doll showing my new design.

I claim:

The ornamental design for a doll as shown.

LEONORE BUBENHEIM.
